(57) **CLAIM**

The ornamental design for a cup cover, as shown and described.

DESCRIPTION

FIG. 1 is a front, left and top perspective view of a cup cover, showing my new design;

FIG. 2 is a rear, right and bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The thinner broken lines in the figures depict portions of the cup cover that form no part of the claimed design. The thicker broken lines in the figures represent stitching that form no part of the claimed design.

1 Claim, 8 Drawing Sheets
